No. 853,509.

PATENTED MAY 14, 1907.

L. GODDU.
WELT SHAPING MACHINE.
APPLICATION FILED JAN. 11, 1899.

UNITED STATES PATENT OFFICE.

LOUIS GODDU, OF WINCHESTER, MASSACHUSETTS, ASSIGNOR TO GODDU SEWING MACHINE COMPANY, OF PORTLAND, MAINE, A CORPORATION OF MAINE.

WELT-SHAPING MACHINE.

No. 853,509.

Specification of Letters Patent.

Patented May 14, 1907.

Application filed January 11, 1899. Serial No. 701,834.

To all whom it may concern:

Be it known that I, LOUIS GODDU, of Winchester, county of Middlesex, State of Massachusetts, have invented an Improvement in Welt-Shaping Machines, of which the following description, in connection with the accompanying drawings, is a specification, like letters on the drawings representing like parts.

10 The present invention relates to machines for shaping welts and more particularly to a machine for cutting a stitch receiving groove in one surface of the welt and for simultaneously beveling or skiving the edge of the welt adjacent to the stitch receiving groove.

15 The object of the invention is to produce a simple machine in which the welt will be supported in a manner best adapted for the proper action of the grooving and skiving knives and wherein as it passes beneath the knives it will be held under tension, thus insuring a clean cut and the proper operation of the machine.

20 To the above end the present invention consists of the devices and combinations of devices which will be hereinafter described and claimed.

25 The present invention is illustrated in the accompanying drawings, in which

30 Figure 1 shows a front elevation of a machine embodying the same, Fig. 2 is a top or plan view of the machine shown in Fig. 1, Fig. 3 is a much enlarged detail showing the clamping or tension devices and the skiving knife. Fig. 4 is an enlarged detail in the dotted line α Fig. 3, looking to the right showing the grooving knife and skiving knife. Fig. 5 is an enlarged sectional detail of the tension clamp acting on the welt. Fig. 6 35 shows the welt with the knives in position to cut the stitch receiving groove and bevel the edge of the welt, and Fig. 7 shows a portion of the finished welt.

40 Similar letters of reference will be used to designate corresponding parts throughout the specification and drawings.

45 In the drawing A designates the head or frame which in practice will be preferably supported on a suitable column A' which 50 rises from the floor. The head A has two laterally projecting arms A², A³ and an overhanging knife support a, which is preferably formed integral with the head A and projects

forwardly therefrom as clearly shown in Fig. 4 of the drawing.

55 The knife support a supports the grooving knife a⁵ and the skiving knife a⁶ which as clearly shown in Fig. 4 of the drawing are inclined toward each other and are secured to the knife support a, by means of clamping plates a⁷ and a⁸ which are grooved to receive the shanks of the knives and which are held to the knife support a by the clamping screws a⁹ and a¹⁰.

60 Supported by the frame or head A at the front thereof, and beneath the over-hanging knife support a, is a block c to which is secured by means of a set screw c¹, a main welt support c², said support c² having a curved upper face over which the welt is drawn and 65 being vertically adjustable on the block c whereby to adjust said support with relation to the auxiliary welt support. One edge of the work support c² is provided with a vertical guide flange c' which constitutes one side 70 of a guide way for the welt as it passes through the machine.

75 Located to one side of the main welt support c² is an auxiliary welt support which is preferably formed by a roller b' mounted to 80 turn on a stud b, the roller being so positioned with relation to the main support c² so as to cause the curved upper surface of the main support c² to merge into and be continued by the periphery of the roll b'. 85

At the rear of the head A there is a tubular extension or bearing d in which is mounted a rock shaft d' shown in dotted lines Figs. 1, 2 and 3. At its forward end the rock shaft d' is provided with an arm d² fixedly secured 90 thereto and to which is secured by a set screw d³ a clamping or tension bar d⁴, said bar d⁴ having on its under side an edge plate d⁵ forming the other side of the guide way for the welt. The bar d⁴ is adjustably connected 95 to the arm d² so that the guide d⁵ may be adjusted toward and away from the guide c' in accordance with the varying widths of welt which are passed through the machine.

100 The clamping bar d⁴ is held in engagement with the welt w and engages said welt in advance of the point of action of the grooving and skiving knives, said bar being forced down by means of a spring e, one end of which is connected with an arm d⁶ secured to 105 the rock shaft d', and the other end of which

is connected to some fixed part of the frame of the machine.

From the foregoing it will be noted that the tension bar d^4 may be raised and turned back against the resistance of the spring e when it is desired to insert the welt beneath the knife carrier a and upon the work supports c^2 and b' and that thereafter the tension bar may be thrown back to occupy the position shown in the drawing whereby to exert a tension on the welt as said welt is drawn from the machine to secure the proper action of the knives thereon.

As shown in the drawing, the machine is arranged to receive a welt wound on a reel or support, one end of which is passed over the work support and beneath the knives and secured to a winding shaft whereby when the winding shaft is revolved the welt will be drawn beneath the knives and from the reel and wound upon the winding shaft.

The reel is shown at f and is mounted on a stud f' held in the arm A^2 of the head A . The welt passes from the reel under the clamp d^4 and over the main support c^2 and the auxiliary support b' between the guides d^5 and c' , and its end is placed in a slot formed in the end of a shaft g mounted in suitable bearings in the arm A^3 of the head A .

The shaft g may be revolved by a crank or any other suitable means, but as shown in the drawing it is provided with a fast pulley h having a long central sleeve on which is placed a loose pulley h' , a suitable belt h^2 being used to rotate the fast pulley and shaft and thus draw the welt through the machine, so that the grooving tool may cut the groove w^1 and the knife a^6 bevel or skive the edge adjacent to the groove w^1 at w^2 . Instead of mounting the welt on a reel as shown in the drawing, the welt coil may be supported in a suitable holder in the manner to permit its turning therein and the withdrawal of the welt from the outer side of the coil as shown in Fig. 1.

It will be noted that the axes of the reel f' and the shaft g are located below the plane of the surface of the main work support c^2 and that by reason of the fact that the welt is drawn from the reel from the under side of the coil upwardly and is wound on the shaft g so that its angle or line of draft as it passes from the knives is being constantly

increased that the welt is buckled or bent as it were where it passes over the work support c^2 and held under tension which results in the proper presentation of the welt in the best manner for the operation of the knives.

Having described the construction and mode of operation of my invention, I claim as new and desire to secure by Letters Patent of the United States:—

1. In a machine for grooving and skiving welts, the combination with a welt support having a curved face over which the welt passes, of means for bending a welt over the welt support and grooving and skiving knives arranged to act on the stretched upper surface and edge of a welt respectively, substantially as described.

2. In a machine for grooving and skiving welts, the combination with a main welt support having a curved face, of means for bending a welt over the welt support an auxiliary rotary support located adjacent to the main welt support and grooving and skiving knives arranged to act on the upper surface and edge of the welt respectively, substantially as described.

3. In a machine for grooving and skiving welts, the combination with the grooving and skiving knives, a welt support provided with a guide flange, a spring pressed tension bar provided with a complementary guide flange, and means for adjusting the tension bar so as to adjust the guide flange carried thereby toward and from the guide flange on the work support, substantially as described.

4. In a machine for grooving and skiving welts, the combination with the over-hanging knife carrier, and grooving and skiving knives adjustably supported therein, a welt support adjustably mounted beneath the over-hanging knife carrier, and a swinging spring pressed arm carrying a tension bar to act on the welt to maintain the tension thereon during the operation of the machine, substantially as described.

In testimony whereof, I have signed my name to this specification, in the presence of two subscribing witnesses.

LOUIS GODDU.
